UNITED STATES PATENT OFFICE.

FRANÇOIS CHARLES THIEL, OF PARIS, FRANCE.

MACHINE FOR THE TORREFACTION OF COFFEE.

SPECIFICATION forming part of Letters Patent No. 699,426, dated May 6, 1902.

Application filed August 3, 1901. Serial No. 70,779. (No model.)

To all whom it may concern:

Be it known that I, FRANÇOIS CHARLES THIEL, a citizen of the Empire of Austria-Hungary, and a resident of Paris, France, have invented certain new and useful Improvements in Coffee-Roasters, of which the following is a specification.

The object of this invention is a torrefying-machine provided with a sphere having a compound rotative movement assuring an equal torrefaction of all substances placed therein and can be used for torrefying, drying, or mixing any substances. It can also be used for polishing metals and may be heated by any suitable heating device. The sphere is so arranged that the compound rotative motion can be changed into a single rotative movement by altering the axis of its rotation.

In the accompanying drawings, Figure 1 is an elevation view of the device. Fig. 2 is a vertical section on A B of Fig. 1 with the cap taken off, the sphere being in position for a compound movement. Fig. 3 shows the same section as in Fig. 2, but with the sphere in position for a single movement.

The device consists of a hollow metal sphere 1, provided at each end with pivots 2 3, diametrically opposite each other. These pivots can turn freely in two circular holes made 30 diametrically opposite each other in a suitable metal ring 4, provided at the extremities of a diametrical line at right angles to the axis with the small pivots 2 3 and the enlarged part 9 provided with a cylindrical hole.

35 The reference-numeral 7 represents the spindle of the crank 8, the end of the said spindle being screw-threaded and fastened to the ring 4 by means of a nut 10. The cylindrical hole allows the passage at 9 of a spindle, to the end of which is suitably fastened the toothed wheel 12.

Outside the ring 4, which turns freely upon the spindle of the wheel 12, this spindle is provided with a square part 11 and ends in 45 a cylindrical part 13, the object of which will be hereinafter described. The said spindle by means either of its square or cylindrical part rests on the bottom of a notch 14, made in the wall of the receptacle 15, containing 50 the source of heat, and the spindle 7 of the crank rotates in a vertical notch 16, made in the cylindrical side of the said receptacle.

This wall is strengthened by the plates 17 and 18, riveted thereon. A toothed wheel 19, fixed to the sphere 1, gears with the wheel 12. The 55 toothed wheel 19 is of a smaller diameter than the wheel 12, causing an equatorial point of the sphere after having performed curves to return after a certain number of revolutions determined by a certain proportion in the diameters of the wheels 19 and 12 to its starting-point, and so on. By way of example, for the proportion 18:24 the said point returns to its starting-point after three revolutions of the metal ring. 60

The two ends of the strengthening-ring 20, fixed to the edge of the receptacle 15, are bent outwardly, and each of them is provided with a hole 21, through which passes a peg in order to prevent the spindle 7 from leaving its notch during the rotation. 65

The sphere is furnished with an opening for filling and emptying purposes, which may be covered with a plate 22, having a handle 23 sliding in the guides 24. A suitable stop 70 25 limits the length of the stroke of this plate.

The manner of using this device is as follows: If it is desired to give a simple rotative motion to the sphere, the shaft of the wheel 12 is arranged in such a way that the cylindrical portion rests in the slot 14. If then the handle 8 is rotated the said shaft will rotate freely in the slot 14 and the ring 4. The same rotative motion will be conveyed to the sphere 1 with its wheel 19 and to the wheel 12 85 with its shaft. If a compound motion of the sphere is required, the shaft of the crank is pushed toward the interior of the receptacle above mentioned. The square portion 11 of the shaft of the wheel 12 engages the slot 14. 90 The said shaft is thus rendered immovable. The rotative movement imparted by the crank to the ring 4, and consequently to the sphere 1, produces, by the gearing of the wheel 19 with the fixed wheel 12, a compound movement of the sphere in such a way that when used for torrefaction all parts of the surface of the sphere come successively in contact with the direct flames of the source of heat and are thus equally heated. If a mixing of 95 substances in the sphere is desired, this will be effected very thoroughly. In order to bring the device back to a position corresponding to a simple rotation of the sphere, 100

105

the shaft 7 is withdrawn. The cylindrical part 13 is then placed in the notch 14.

Having now fully described my invention, what I claim, and desire to secure by Letters Patent, is—

- 5 1. In a machine of the character described, the combination with a casing, a ring rotatably secured in said casing, a spindle, a square and cylindrical end formed on said spindle, a spherical casing revolvably mounted in said ring, wheels 12 and 19 arranged within said ring for revolving said spherical casing, and means to rotate said ring.
- 10 2. In a coffee-roaster, the combination of an outer casing, a furnace arranged in said casing, a crank-shaft secured in said casing,

a ring rigidly attached to said shaft, a spindle passing through said ring diametrically opposite said crank-shaft, a square and cylindrical end carried by said spindle, a wheel 12 attached to said spindle arranged within said ring, a wheel 19 of a smaller diameter meshing with said wheel 12, and a spherical casing secured in said ring rotatably driven by said wheels, substantially as described. 20

25 In testimony whereof I have hereunto set my hand in presence of two witnesses.

FRANÇOIS CHARLES THIEL.
